UNITED STATES PATENT OFFICE.

JAMES E. CLOUGH AND WILSON H. STILWELL, OF PARIS, AND ARTHUR R. FUGINA, OF LOUISVILLE, KENTUCKY.

RAIL-CONTACT CIRCUIT-CONTROLLER.

1,312,101.

Specification of Letters Patent.

Patented Aug. 5, 1919.

Application filed August 15, 1917. Serial No. 186,334.

To all whom it may concern:

Be it known that we, JAMES EDGAR CLOUGH, WILSON HEATH STILWELL, and ARTHUR R. FUGINA, citizens of the United States, residing, respectively, the first two at Paris, county of Bourbon, the latter in Louisville, county of Jefferson, all in the State of Kentucky, have invented a new and useful Rail-Contact Circuit-Controller, of which the following is a specification.

This invention relates to means for controlling electric circuits, adapted to be actuated upon the depression of a rail by a passing train, which when primarily actuated upon the passing of a train in either direction, will not be changed by subsequent depressions of the rail, until the train has passed beyond the zone of the device, and which consequently may be used on single track railways.

The invention consists, essentially, in the combination with a railway track, having points disposed a spaced distance apart, in a rail thereof, and arranged to be depressed by each wheel passing along the rail, of circuit closing means positioned intermediate the depressible points, and having mechanically operable connections therewith.

An object of the invention is to provide circuit controlling means of the character described, having a plurality of connections with a railway rail, and adapted to be actuated from a normal position, by an impulse received upon a depression of the rail at either of said connections, subsequent impulses due to a depression at either of said connections prior to a return to normal, tending to maintain the position assumed in obedience to the primary impulse.

A further object is to provide a device as characterized, which shall be economical in construction, easily installed, efficient in operation and durable in service.

With the foregoing and other objects in view, the invention consists of the novel construction and arrangement of parts illustrated in the accompanying drawings, which form a part of this specification, wherein is set forth an embodiment of the invention, but it is to be understood that such changes and modifications may be resorted to as come within the scope of the appended claims.

In the drawings wherein similar reference

characters designate like parts in the several views, Figure 1, is a plan view, of a portion of a railway track showing an embodiment of the invention installed in connection therewith, the cover of the controller box being removed: Fig. 2, a side elevation of the same with the box cover in place: Fig. 3, a side elevation (on an enlarged scale) of the spring plate in position: Fig. 4, a diagrammatic plan: Fig. 5, a plan view (with cover removed) of the controller box containing the selective mechanism: Fig. 6, a section on line 6—6 of Fig. 5: Fig. 7, a section on line 7—7 of Fig. 6: Fig. 8, an end elevation of a terminal bearing: Fig. 9, a side elevation of the bearing: Fig. 10, a perspective view of the selector arm.

Referring now to the drawing wherein is shown a portion of a railway track, comprising a rail —11— of conventional design which is secured upon cross ties, or sleepers —12— by suitable means. Tie plates —13— are secured to certain of the ties, and springs —14— are positioned between the tie plates and the rail, at right angles to the rail. The spring plates have a central arched portion —15— which yields under the weight of passing rolling stock, permitting a depression of the rail of approximately $\frac{1}{8}$ of an inch. The spring plate is retained in place by suitable means such as bolts —16— which pass through slots —17—, extended in from the ends thereof, which permit extension of the plate as it flattens out, and through openings in the tie plate. At a suitable point along the track a weather proof controller box —19— is positioned, preferably between two cross ties, where it is supported by suitable means such as bars —20—, in such a manner that the top of the box will be below the level of the rail. The box is provided with a removable cover —21—. A suitable packing is placed in a space —22— between the cover and the upper edge of the walls of the box to prevent the entrance of moisture. Pairs of oppositely disposed ears —23—, —24— are secured to the sides of the box. A locking arm —25— is pivotally connected to the ear 23 and an eye bolt —26— is pivotally connected to the ear 24. The cover may be secured in place by folding the locking arm thereacross and engaging it with the eye bolt. A nut —27—, on the eye bolt, is then

screwed down against the arm, forcing the cover down upon the box. A hasp —28—, which is hinged to the nut, is then turned down and engaged with a staple —29— which extends from the top of the arm, and a locking element (not shown) such as a padlock inserted through the staple. A block —30— is erected on the bottom of the box interiorly thereof, on a medial longitudinal line. On one side of the block 30, at the forward end thereof and extending forward therefrom a mounting strip —31— of insulating material such as fiber, is secured by suitable means such as bolts —32—. On this strip are mounted a plurality of binding posts —33, 35, 37— which are in electrical connection respectively with a heel contact spring —34—, a stirrup contact spring —36—, and a movable contact finger —38— which are mounted on the opposite side of the strip and extend upward parallel with and at varying distances therefrom. Electrical conductors lead from the respective binding posts through an outlet —40— to distantly positioned electrically operated mechanism. A block —41— pivotally mounted upon the block —30— near the forward end thereof carries a selector bar —42— which is arranged transversely of the box. Centrally of this bar, on the forward side thereof, an arm —43— extends. This arm is insulated from the bar by a fiber strip —44—, and is provided on its forward end with a slot —45— adapted to receive the contact finger 38, whereby movement of the selector bar will be communicated to the contact finger moving it into contact with one or the other of the contact springs. A pair of oppositely disposed springs —46— which are secured to the sides of a projection —47— at the rear of the block 30, extend forward and bear against the sides of the pivot block 41. These springs oppose any movement of the pivot block and serve to return it, and associated parts to normal position when deflected therefrom. At spaced distances from the controller box, on each side thereof, brackets —50— are positioned, and are secured to the tie plates on which the spring plates are located in proximity to the rails. These brackets comprise parallel spaced walls —51, 52— joined by an arched portion —53—, and a base —54— extended from the wall 52, by means of which they are attached to the ties. A pipe —55— extends along the rail, from the box to the bracket, one end of the pipe being received in a projection or boss —56— on the box and the other end in the wall 51 of the bracket. A shaft —57— is run through the pipe and projects into the box. The outer end of the shaft is journaled in the wall 52 of the bracket and the inner end in a boss —58— on the inner side of the wall of the box. A dog —59—

is secured on the shaft between the walls of the bracket, by suitable means such as a taper pin and a toe —60— thereof bears upon the flange of the rail. A lever —61— is secured on the inner end of each of the shafts by suitable means, as herewith illustrated said means comprising a looped portion —62— disposed about the shaft and clamped thereon by means of a bolt —63—. The free end of the lever bears an angular projection or tip —64—, the end of which is beveled off forming a knife edge —65—, the arrangement being such that when either lever is raised it will engage the selector bar near the end thereof. If the selector bar is in its normal position the tip will come into contact with the forward side thereof and draw the end engaged toward the rear of the box. If while the parts are in this position the lower lever is actuated the tip thereof will pass behind the advanced end of the bar and hold it in actuated position. A pin —66— erected on the floor of the box extends upward through a perforation —67— in the lever and serves as a guide therefor. A spring —68— disposed about the pin and bearing respectively on the floor and against the lever tends to force the latter upward. This movement is resisted by the dogs 59 which bear upon the rail. The arrangement is such that the movement of the levers is controlled by the deflection of the rail which in turn is actuated by the passage of the rolling stock. A rod —69— disposed transversely of the box, a spaced distance above the levers 61, serves as a stop to limit their upward movement. The relative positions of the dogs 59 and the levers 61 on the shafts is such that when the rail is in its normal, or elevated position, the levers are in their lowest position.

As a train approaches the apparatus, say in the direction of the arrow, the weight thereof overcoming the tension of the spring plate depresses the rail whereupon the dog at that point being free to move, the spring 68 will force the corresponding lever upward, the chisel pointed end of the lever tip will slide over the bevel edge of that end of the selector bar moving it in the opposite direction. This movement of the selector bar through the medium of the arm 43, causes the contact finger to contact with a spring, as the heel contact 35, whereupon an impulse is transmitted which actuates a signal indicating the approach of a train and the direction from which it is coming. As the train passes over the plate, on the other side of the selector box, it depresses the rail at that point and the corresponding selector lever is raised by its spring 68, but, as that end of the selector bar has moved forward, the tip of the lever passes behind the bar, thereby holding it in the actuated

position until the train has passed. It will be observed that upon the depression of a spring plate, by an approaching train, contacts will be made to transmit a signal corresponding to the direction in which the train approaches, that subsequent depression of a second plate will not affect the signal transmitted, and that the signal will be sustained until the train has passed over all plates connected with the controller box. When the rearmost wheel of a train passes over the depressible point in the rail on the near side of a selector-box the rail at that point will return to its normal position and through the medium of the dog 59, and shaft 57, will lower the associated lever 61, disengaging it from the selector-bar 42, which would then return to its normal position, but that it is still held by the other selector-lever 61, which is upheld by reason of the train passing over the depressible-point, on the far side of the selector-box, which controls it. When the rearmost wheel passes over the depressible-point on the far side of the selector-box, the lever 61 actuated therefrom will be lowered from its engagement with the selector-bar, which will then be returned to its normal position by means of the springs 46, carrying with it the contact spring 38. The parts are now in their normal position ready for actuation by a train approaching from either direction.

It is to be understood that while the operation of the device is explained in connection with an open circuit, its use is contemplated with a closed circuit, and claims directed to an open circuit are to be read as applying with equal force to a closed circuit.

Having thus described our invention so that anyone skilled in the art pertaining thereto can make and use the same, we claim:

1. In an apparatus as characterized, a plurality of contact springs, a contact finger adapted to be contacted with selected ones of said springs, a plurality of means adapted to actuate said finger, a railway rail, a plurality of depressible points along said rail and operative connections between said actuating means and said depressible points.

2. In combination with a rail, a plurality of cross ties to which said rail is attached, the rail being at one point movable relative to an adjacent tie, a plurality of contact springs, a flexible contact finger, means for flexing said finger, and operative connections between said flexing means and said movable point in the rail.

3. In combination, a rail adapted to be depressed at a given point by a passing train, a plurality of contacts, a member adapted to close certain of said contacts, means adapted to actuate said member, and oper-

ative connections between said means and said depressible point in the rail whereby the closure of the contacts is controlled by the movement of the rail.

4. In combination, a rail adapted to be depressed at determined points by a passing train, a plurality of contacts, a member adapted to close certain of said contacts, a plurality of means adapted to actuate said member, and operative connections between said actuating means and said depressible points in the rail whereby closure of the contacts is controlled by the movements of the rail.

5. In combination, a plurality of actuating members, a plurality of contacts, a movable finger adapted to close certain of said contacts, a selector bar adapted to move said finger, said bar lying within the zone of action and adapted to be shifted by said members, a rail adapted to be depressed at determined points, operative connections between the actuating members and said depressible points in the rail whereby depression of the rail at a point will allow the complementary actuating member to shift said selector bar thereby removing it from the active zone of the other actuating member.

6. In combination, a plurality of contacts, a movable finger adapted to close on selected contacts, a selector bar adapted to move said finger, levers adapted to actuate said bar, a rail adapted to be depressed at determined points, operative connections between said levers and said depressible points whereby depression of the rail at a point will allow the complementary lever to actuate the bar.

7. In combination with a rail, a plurality of cross-ties to which it is secured, resilient supporting means positioned between said rail and a tie, a shaft, a lever extended from one end thereof, a dog secured on the other end thereof and bearing on the rail in proximity to said supporting means, and electric contacts adapted to be actuated by said lever upon the depression of the rail.

8. In combination, a rail adapted to be depressed at given points, a box positioned between said points in proximity to said rail, a plurality of contacts in said box, a member adapted to close certain of said contacts, a shaft extending from each side of the box to a depressible point, a lever extended from the inner end of each shaft adapted to actuate said closing member, a dog on the outer end of each shaft said dogs bearing on the rail in proximity to a depressible point opposing movement of the levers except when the rail is depressed.

9. In apparatus as characterized, a box, oppositely disposed contacts therein, a movable contact finger, a pivoted block, a bar secured to said block, an arm extended from

- said bar and engaged with said finger, means for normally holding the block and assembly in such position that the finger does not make contact, levers adapted to engage respectively with opposite ends of the bar to move the finger to or fro, shafts to the inner ends of which said levers are secured, a rail adapted to be depressed at points spaced each way from the box and a dog secured on the outer end of each shaft, a toe of the dog bearing on the rail in proximity to the depressible point and opposing movement of the levers except when the rail is depressed.
- 10 15. In apparatus as characterized, a box, oppositely disposed contacts therein, a movable contact finger, a pivoted block, a bar secured to said block, an arm extended from said bar and engaged with said finger, means for normally holding the block and assembly in such position that the finger does not make contact, levers adapted to engage respectively with opposite ends of the bar to move the finger to or fro, shafts to the inner ends of which said levers are secured, a rail adapted to be depressed at points spaced each way from the box and a dog secured on the outer end of each shaft, a toe of the dog bearing on the rail in proximity to the depressible point and opposing movement of the levers except when the rail is depressed.
- 20 25. 10. In apparatus as characterized, a box, oppositely disposed contacts therein, a movable contact finger, a pivoted block, a bar secured to said block, an arm extended from said bar and engaged with said finger, means for normally holding the block and assembly in such position that the finger does not make contact, levers adapted to engage respectively with opposite ends of the bar to move the finger to or fro, shafts to the inner ends of which said levers are secured, a rail adapted to be depressed at points spaced each way from the box and a dog secured on the outer end of each shaft, a toe of the dog bearing on the rail in proximity to the depressible point and opposing movement of the levers except when the rail is depressed.
- 30 35. 11. In a circuit controller as characterized, a rail adapted to be depressed at given points by passing trains, a plurality of contacts, a contact finger, a member adapted to move said finger in opposite directions, means adapted to be brought into engagement with said member to shift the same in one direction, other means adapted to be brought into engagement with said member to shift it in a reverse direction, and mechanical operative connections between said means and said depressible points in the rail whereby movement of the rail permits functioning of the means.
- 40 45. 12. In combination with a rail, a plurality of cross ties to which it is secured, resilient supporting means positioned between said rail and certain ties spaced a distance apart whereby the rail may be depressed at said point, a contact finger positioned intermediate said depressible points, shafts journaled in proximity to and substantially parallel with the rail, a lever on the inner end of each shaft adapted to actuate said contact finger, means tending to rotate the respective shafts, and a dog on the outer end of each shaft adapted to bear on the rail in proximity to a depressible point opposing the action of said rotating means whereby

the shaft is turned only when the rail is depressed.

13. In apparatus as characterized, a movable contact member, means for moving said member, a rail, having a depressible point in the length thereof and mechanical connections whereby movement of the contact member is controlled by the movement of the rail at said point. 65

14. In apparatus of the character described, a movable contact member, means for moving said member, a rail having depressible points in the length thereof, and mechanical connections between said means and said points whereby movement of the rail at either of the points will permit functioning of the means. 70

15. In apparatus as characterized, a movable contact member, a rail having depressible points in its length, means for moving the member in a given direction, means for moving the member in another direction, and mechanical connections between said means and respective depressible points 85 whereby the depression of the rail at either of the points will permit the said means to function, the construction and arrangement being such that an initial depression of the rail at either of the points will result in a 90 movement of the contact member, and that a succeeding depression at another point will confirm said movement.

16. In apparatus as characterized, a flexible contact member, and a plurality of 95 means adapted to act upon said member, either of said means being initially actuatable and serving in accordance with the sequence of their actuation to flex said member or to maintain it in a flexed position. 100

17. In apparatus as characterized, a flexible contact member, a plurality of means adapted to flex said member, a rail having depressible points in its length, and operative connections between said means and respective depressible points whereby movement of the rail at said points will permit functioning of the means, said means serving according to the sequence of their functioning to flex said member or to hold it in 110 a flexed position.

18. In apparatus as characterized, a movable contact member, selectively operatable means adapted to act sequentially upon said member, initially operated means moving 115 the member in a predetermined direction, and subsequently operated means holding the member in the actuated position.
